[57] CLAIM

The ornamental design for an armrest enclosure for an automobile telephone, as shown and described.

DESCRIPTION

FIG. 1 is a side elevational view of an armrest enclosure for an automobile telephone showing my new design; FIG. 2 is a top plan view thereof; and FIG. 3 is a perspective view of the armrest enclosure with the hinged top-lid in an opened position.

The bottom side of the armrest enclosure is plain and unornamented and follows the contours of front side and side edge shown in FIG. 3. The unseen side is also plain and unornamented and follows the contour of the side shown in FIG. 1 but without the key-plate or mounting means shown in FIGS. 1 and 3.

FIG. 1

FIG. 3
